UNITED STATES PATENT OFFICE.

WILLIAM E. GIBBS, OF FANWOOD, NEW JERSEY, ASSIGNOR TO ALEXANDER C. HUMPHREYS AND ARTHUR G. GLASGOW, OF NEW YORK, N. Y., (TRADING UNDER FIRM NAME OF HUMPHREYS & GLASGOW.)

PREPAYMENT FLUID-METER.

SPECIFICATION forming part of Letters Patent No. 677,974, dated July 9, 1901.

Application filed September 13, 1900. Serial No. 29,867. (No model.)

To all whom it may concern:

Be it known that I, WILLIAM E. GIBBS, a citizen of the United States of America, residing in Fanwood, in the county of Union and State of New Jersey, have invented certain new and useful Improvements in Prepayment Fluid-Meters, of which the following is a true and exact description, reference being had to the accompanying drawings, which form a part thereof.

My invention relates to prepayment fluid-meters, such as are used, for instance, in the distribution of gas; and the object of my invention is to at once simplify the construction of the prepayment mechanism and give it a construction which will insure in great measure its correct and safe operation.

The essential feature of my invention consists in the application to mechanism for opening and closing the fluid-conduit leading to the meter of devices in the nature of a Geneva stop-motion, of which a coin of proper size forms an essential element.

How my invention is best embodied and with what devices securing it against improper manipulations it is provided will be best understood as described in connection with the drawings, in which my invention is illustrated, and in which—

Figure 1 is a front view of a gas-meter having my device attached to it. Fig. 2 is an elevation taken on the section-line 2 2 of Fig. 4. Fig. 3 is a cross-sectional elevation taken on the section-line 3 3 of Fig. 6. Fig. 4 is a plan view taken on the section-line 4 4 of Fig. 6. Fig. 5 is an enlarged view of a detail shown in Fig. 4. Fig. 6 is an elevation taken on the section-line 6 6 of Fig. 4. Fig. 7 is a cross-sectional elevation taken on the section-line 7 7 of Fig. 6. Fig. 8 is a front elevation taken on the section-line 8 8 of Fig. 4. Fig. 9 is a side elevation taken on the section-line 9 9 of Fig. 6. Fig. 10 is a perspective view of a rotatable plug-cock casing used in connection with my device in the construction illustrated.

Fig. 11 is a perspective view of the plug-cock. Fig. 12 is a perspective view of the slotted drum which receives and moves the coin. Fig. 13 is a plan view showing the end of the shaft O² and the gear-wheels connected there-

with. Fig. 14 is an elevation taken on the section-line 14 14 of Fig. 13 and showing the rear of the two wheels Q and P.

A, Fig. 1, indicates the gas-meter, which is of usual construction, B indicating the recording-dials of the meter and C a worm driven by the mechanism in the meter and in turn driving a shaft C', which shaft, as shown, (see Figs. 4 and 6,) is hollow and has its ends supported on the stud C², grooved as indicated at c², the hollow shaft C' being kept from longitudinal movement on the plug by a setscrew C³, projecting into the groove.

C⁴ is a gear-wheel secured on the end of the shaft C' and contained in a chamber C⁵, partially formed by and normally closed by the removable cap C⁶, held in place at bottom, as shown, by a pin C⁷ (see Fig. 6) and at top by a lock-bolt passing through the eyes, (indicated at c⁸.)

Any convenient mechanism for opening and closing the fluid-conduit leading to the meter may be used in connection with my invention. As shown, I have illustrated my invention in connection with the throttling mechanism described and shown in Green's patent, No. 606,625, of June 28, 1898, with certain modifications adapting said mechanism for my purposes.

To resume the description of the drawings, D indicates a casting having formed in it the chamber D', adapted to receive the stop-wheel F⁹ and gear-wheel G⁵, to be hereinafter described.

D² is a chamber formed in the casting and connecting with the chamber D', said chamber D² being adapted to receive the drum I.

D³ is a third chamber formed in the casting, adapted to receive the stud O and its continuation—the worm-wheel O'. From the bottom of the chamber D² extends an opening D⁴, through which the coin falls into a receptacle M, d⁴ indicating a perforated lug adapted to register with a perforation in a lug M' of the removable receptacle, the receptacle being held in place through the action of a lock, as indicated in Fig. 1.

D⁵ (see Fig. 4) indicates a bearing for one of the projecting studs upon which the drum I is supported.

D⁶ indicates a slot in the top of the chamber D², through which the coin is inserted.

D⁷ (see Figs. 1, 4, and 7) is an opening in the front of the casting D, across which extends the bar indicated at D⁸.

E indicates a second casting forming with the casting D the various chambers of the apparatus, E' indicating the flanges and abutting parts where the casting E comes in contact with and is secured to the casting D.

E² indicates the part of the casting E which forms the rear wall of the chamber D², E³ indicating a bearing formed in the wall for the rear projecting stud, on which the drum I is supported, and E⁴ (see Fig. 3) indicating a slot formed through this wall, through which coins rejected as of insufficient size are shunted.

E⁵ is a chamber at the rear of the casing E, in communication with the conduit E⁷, as shown in Fig. 7, and, through a conical bearing e⁵, with an internal chamber E⁶, which communicates with a conduit E⁸.

e⁶ indicates a conical bearing on the side of the chamber E⁶ opposite to that provided with a bearing e⁵.

F may be described as a hollow rotatable plug-cock. Its smaller end opens into the chamber E⁵, and it is provided with circumferential bearing-surfaces which fit against the bearings e⁵ and e⁶, and is also on its inner faces provided with the conical bearing-faces, (indicated at F' and F².)

F³ indicates a stop-motion wheel of the kind familiar in the Geneva stop-motion, said wheel being, as shown, formed on a prolongation of the rotatable plug-cock F.

F⁴ indicates a lateral opening through the wall of the cock F, connecting its interior with the chamber E⁶, and F⁵ is an annular prolongation of the cock F, on which, as shown, a scale of numerals is marked, a projecting pin f⁵ occupying the position of the zero in the scale.

G is the plug-cock, working in the hollow rotatable plug-cock F. It consists, as shown, of two conical portions (indicated at G' and G³) which bear on the conical bearings F' and F² of the hollow cock F, the smaller end G' being open and the two bearing-surfaces being connected by a longitudinally-extending cross-bar G², fitting against the inside of the cock F and adapted to register with and close the slot F⁴ when the cock G is turned to proper position.

G⁴ indicates an annular prolongation of the plug-cock G, to which is secured or on which is formed the worm-wheel G⁵, which, as shown, is formed with a slot G⁶, lying opposite to the scaled face F⁵ of the cock F.

g⁶ indicates a stop projection from the rear side of the wheel G⁵, adapted to be engaged by the stop-pin f⁵ on the cock F.

g³ (see Fig. 4) indicates a pin-receiving perforation; H, a pin resting in said perforation and having a head H', which rests against the center of the cross-bar D⁸, h indicating a spring

acting against said head H' and against a plug-cock G to thrust it into the conical bearings of the hollow cock F.

I indicates a drum situated in the chamber D² and having from its opposite faces the projecting studs I' and I², which form its bearings. The bearing-stud I² is slotted at the end, as indicated at i², Fig. 4, so that it may be engaged with a device in the nature of a cyclometer, (indicated at N,) whereby the rotations of the drum can be recorded, and the bearing-stud I' having attached to it the hand-wheel, (indicated at i'.) The drum I, as shown, has an edge groove, (indicated at I₁), so as to afford clearance for the worm-wheel G⁵. Near its opposite end it is provided with a series of detent-openings (indicated at I⁴) which are preferably arranged symmetrically, except at two points—that is to say, the detent-opening I⁴, (see Fig. 12,) which is intended to engage the ratchet-pawl when the drum is in coin-receiving position, is placed at a somewhat greater distance from the adjacent perforations I⁴ than the adjacent perforations I⁴ are distant from each other. Again, the perforations I⁴ are on the opposite side of the drum intermittent for a distance, as indicated at I⁵, this intermittent portion of the ratchet lying beneath the pawl when the drum is turned to the position where it should deliver its coin, permitting considerable freedom of backward and forward movement at this point.

I⁶ indicates a circumferential groove approximately at the center of the drum I, and I⁷ is the coin-receiving slot, extending transversely through the drum I in an oblique direction, as best shown in Fig. 3, this slot having a narrowed portion, (indicated at i⁷,) whereon the coin of proper dimensions is arrested, and a narrow extension (indicated at I⁸) through which coins of less than determined size are rejected and permitted to fall out through the slot E⁴.

I⁹ (see Fig. 5) is a perforation extending radially from the bottom of the groove I⁶ toward the slot I⁷, with which it communicates through a narrowed extension i⁹.

I¹⁰ is a pin-hole extending from the side of the drum I, through which a locking-pin is inserted into the perforation I⁹.

J is a plug moving in the perforation I⁹ and having an extension J' of smaller diameter, which projects into the extension i⁹. The plug J has a reduced neck, as indicated at J², and the spring J³ normally holds it in the position indicated—that is to say, with its face flush with the bottom of the groove I⁶ and its extension J' flush with the side of the slot I⁷.

J⁴ is a stop-pin extending through the perforation I¹⁰ and serving to arrest the plug in the position shown in Fig. 10 while permitting it to move backward, so as to project into the groove I⁷ on pressure being applied to its face.

K (see Fig. 8) is a ratchet-pawl pressed by

a spring K' against the ratchet portion I⁴ of the drum I.

L (see Fig. 2) is a ratchet-pawl pressed by a spring against the bottom of the groove I⁶ in the drum I, the point of the pawl being of such size and so placed as to enter the perforation I⁹ when it is not protected by the plug J.

L' is a spring attached to and extending from the pawl L and supporting on its end a stop-block, (indicated at L².)

M has already been described as the coin-receiver, and N is a cyclometer-recorder.

O (see Figs. 6 and 7) is a rotating cylindrical plug supported on journals in the chamber D³ and having formed on it the worm, (indicated at O'), which engages with the worm-wheel G⁵. The bearing O² of the worm-plug O extends into the chamber C⁵ and serves as a bearing for the loosely-mounted gear-wheel P, beyond which it has attached to it the gear-wheel indicated at Q. The gear-wheel P (see Figs. 9, 13, and 14) has a portion of its teeth omitted, as indicated at P', and has projecting from its outer face two stop-pins, (indicated at P² and P³.) The gear-wheel Q, which is secured by its hub Q' on the shaft O², has a portion of its teeth omitted, as shown at Q², is provided with a fixed stop Q³, projecting toward the wheel P and so as to be engaged by the stop P², and at the same radial distance from the center of the wheel it is also provided with a series of pin-receiving holes Q⁴.

R indicates a perforated hub adapted to slip over the projecting hub Q' of the wheel Q and formed with a pin-supporting arm R', from which extends a pin R², which can be inserted into any of the holes Q⁴, as shown in Figs. 9 and 13.

S (see Fig. 9) is a spring-stop acting in connection with the teeth of the wheel Q to prevent it from being moved in a reverse direction. Both of the wheels P and Q are normally engaged by the gear-wheel C⁴, as shown in Figs. 6 and 9.

I may say here that the mutilated-wheel construction, as indicated, is not a part of my invention, but is, in fact, an invention of Henry Green. (Shown in his Patent No. 651,481, of June 12, 1900.)

The operation of my device may be described as follows: The parts being normally in position shown in Figs. 2, 3, and 8, rotation of the drum backward is prevented by the engagement of the ratchet-pawl K with the perforation i⁴, and rotation forward is immediately checked by the engagement of the pawl L with the perforation I⁹, a plunger J yielding to the pressure of the pawl and permitting it to enter the perforation. After backward rotation has been checked it is, however, advisable to bring the slot I⁷ back into registry with the slot D⁶, as the pawl K has not engaged any other perforation after leaving the perforation i⁴. A coin of proper size being dropped through the slot D⁶ into the

slot I⁷ is held in said slot, as indicated in dotted lines in Fig. 3, the side of the coin resting against the end pin J'. The drum being 70 rotated toward the stop-wheel F³, the edge of which lies in the groove I⁶, as shown, the pawl L will pass over the perforation I⁹, as the plug J cannot yield to its pressure, being arrested by the coin, and the coin will enter the adjacent slot in the edge of the stop-wheel F³ and will cause the stop-wheel to rotate through an angular distance corresponding to the difference between its slots. After the coin has left contact with the stop-wheel it is dropped 80 through the opening D⁴ into the receptacle N; but if for any reason the coin is not dropped into the receptacle the further rotation of the drum is checked by the coin coming in contact with the stop L², which can be held in 85 the position indicated by any convenient means as well as those indicated. After being so stopped the drum I may be moved backward to bring the coin into position to fall into the receptacle N by reason of the 90 blank portion I⁵ of the ratchet-detents being then opposite to the pawl K. After dropping the coin the drum may be further revolved until its slot I⁷ registers with the slot I⁶, as already described. 95

The stop-motion wheel F³ may be connected with any device or means having the function of opening the fluid-conduit, so as to permit the fluid to flow into the meter. As shown, it is attached to and directly actuates the rotatable plug-cock casing F, and supposing the plug to be in position to cover the slot F⁴ it is obvious that the rotation of the casing will open this slot, moving it away from the cross-bar of the plug for a distance in the construction shown equal to one-tenth of the circumference of the plug. By then inserting another coin in the drum and operating as before described the slot may be moved again away from the plug through an equal distance, 100 and so on, the construction, as illustrated, permitting ten coins to be used consecutively before the stop-pin f⁵ on the rotatable casing comes in contact with the stop and anchoring-pin g⁶ on the worm-wheel G⁵, which prevents further movement of the casing. The 105 position of the cross-bar of the plug-cock with reference to the opening in the casing is at all times indicated by the relationship of the indicating and stop pin G⁶ to the numerals 110 of the scale F⁵. The cock being opened, the gas or other fluid flows through the conduits E⁷, the hollow end of the plug, the chamber E⁶, and the conduit E⁸ into the meter, actuating the mechanism therein, which in turn 115 sets in operation the worm C, which drives the shaft C' and the gear-wheel C⁴ at its end. This gear-wheel engaging both the gear-wheels P and Q, as shown in Fig. 9, causes them to revolve together, and also rotates 120 the shaft O² and through it and the worm O' 125 rotates the worm-wheel G⁵ and the plug-cock G, attached thereto, moving the cross-bar G² toward the slot F⁴ of the casing F. 130

The mutilated gear - wheel construction shown and invented by Mr. Green, as before mentioned, is for the purpose of permitting a change in the amount of gas necessary to move the plug-cock through a determined distance. Thus the parts being in the position shown in Figs. 9, 13, and 14 the two wheels Q and P are rotated together, and the stops P² and Q³ being in contact with each other, as shown in Fig. 14, the wheels continue to rotate together even after the mutilated portion Q² of the wheel Q comes opposite to the gear-wheel C⁴. When, however, in the rotation of the wheels the mutilated portion of the wheel P⁴ and the wheel P comes opposite to the mutilated portion P⁴, the wheel P ceases to revolve until the revolution of the wheel Q brings the stop R² into contact with the stop P³, when again the wheels resume their joint rotation until the mutilated portion Q² of the wheel Q again comes opposite to the gear - wheel C⁴, whereupon the wheel Q remains stationary until the studs P² and Q³ are again in contact, as shown in Fig. 14. It will readily be seen, therefore, that by moving the stop-pin R² the amount of fluid passing through the meter can be made to bear different and any desired ratio to the movement of the plug-cock.

Having now described my invention, what I claim as new, and desire to secure by Letters Patent, is—

1. A fluid-conduit, a meter connected thereto and means for opening and closing the conduit in combination with mechanism actuated by the meter, tending to actuate said means to close the conduit, a slotted stop-motion wheel, as F³, having concave segmental facets between its slots arranged to act upon the means controlling the flow of fluid to open it, a manually - operated coacting drum, as I, adapted to fit in the concave facets of wheel F³ said drum being recessed on one side to clear said wheel and slotted to receive and hold a coin of proper size in position to form a tooth on the drum adapted to engage in a slot of and actuate the wheel F³, and a coin-receiver arranged to receive the coin from drum I after it has actuated the wheel F³.

2. A fluid-conduit, a meter connected thereto and means for opening and closing the conduit in combination with mechanism actuated by the meter tending to actuate said means to close the conduit, a slotted stop-motion wheel, as F³, having concave segmental facets between its slots arranged to act upon the means controlling the flow of fluid to open it, a manually-operated coacting drum, as I, adapted to fit in the concave facets of wheel F³ said drum being recessed on one side to clear said wheel and slotted to receive and hold a coin of proper size in position to form a tooth on the drum adapted to engage in a slot of and actuate the wheel F³, said slot having a prolongation of smaller size to eject coins of improper size, means for preventing the rotation of drum I in a reversed direction

and a coin-receiver arranged to receive the coin from drum I after it has actuated the wheel F³.

3. A fluid-conduit, a meter connected thereto and means for opening and closing the conduit, in combination with mechanism actuated by the meter tending to actuate said means to close the conduit, a slotted stop-motion wheel, as F³, having concave segmental facets between its slots arranged to act upon the means controlling the flow of fluid to open it, a manually-operated coacting drum, as I, adapted to fit in the concave facets of wheel F³ said drum being recessed on one side to clear said wheel and slotted to receive and hold a coin of proper size in position to form a tooth on the drum adapted to engage in a slot of and actuate the wheel F³, said slot having a prolongation of smaller size to eject coins of improper size, means for preventing the rotation of drum I in a reversed direction, a coin-receiver arranged to receive the coin from drum I after it has actuated the wheel F³, and a fixed stop, as L², arranged to engage the coin and prevent the rotation of drum I in case the coin is not dropped into the receptacle.

4. A fluid-conduit, a meter connected thereto and means for opening and closing the conduit in combination with mechanism actuated by the meter tending to actuate said means to close the conduit, a slotted stop-motion wheel, as F³, having concave segmental facets between its slots arranged to act upon the means controlling the flow of fluid to open it, a manually-operated coacting drum, as I, adapted to fit in the concave facets of wheel F³ said drum being recessed on one side to clear said wheel and slotted to receive and hold a coin of proper size in position to form a tooth on the drum adapted to engage in a slot of and actuate the wheel F³, said slot having a prolongation of smaller size to eject coins of improper size, means for preventing the rotation of drum I in a reversed direction, a stop device arranged to prevent forward rotation of the drum, means for moving said stop out of operative position actuated by a coin in the slot of the drum and a coin-receiver arranged to receive the coin from the drum after it has actuated the stop-wheel.

5. A fluid-conduit, a meter connected thereto and means for opening and closing the conduit in combination with mechanism actuated by the meter tending to actuate said means to close the conduit, a slotted stop-motion wheel, as F³, having concave segmental facets between its slots arranged to act upon the means controlling the flow of fluid to open it, a manually-operated coacting drum, as I, adapted to fit in the concave facets of wheel F³ said drum being recessed on one side to clear said wheel and slotted to receive and hold a coin of proper size in position to form a tooth on the drum adapted to engage in a slot of and actuate the wheel F³, said slot having a prolongation of smaller size to eject

coins of improper size, means for preventing the rotation of drum I in a reversed direction, a stop device arranged to prevent forward rotation of the drum, means for moving 5 said stop out of operative position actuated by a coin in the slot of the drum, a coin-receiver arranged to receive the coin from the drum after it has actuated the stop-wheel, and a fixed stop, as L², arranged to engage the coin 10 and prevent the rotation of drum I in case the coin is not dropped into the receptacle.

6. In a prepayment-meter, the combination with a stop-motion wheel, as F³, arranged to open the fluid-conduit, of a manually-operated 15 drum I having a circumferential groove I⁶ and oblique transverse coin-slot I⁷ adapted to hold a coin of proper size with its edge projecting into groove I⁶ in position to engage the notches in the stop-motion wheel and having 20 a narrower prolongation whereby it rejects a coin of improper size, a ratchet-stop for preventing motion of the drum in a reverse direction, a coin-receiver arranged to receive the coin from the drum after it has 25 actuated the stop-wheel and a fixed stop extending into groove I⁶ and acting to engage the coin and prevent rotation of the drum in case the coin is carried over the receiver.

7. In a prepayment-meter, the combination 30 with a stop-motion wheel, as F³, arranged to open the fluid-conduit, of a manually-operated drum I having a circumferential groove I⁶ and oblique transverse coin-slot I⁷ adapted to hold a coin of proper size with its edge pro-

jecting into groove I⁶ in position to engage 35 the notches in the stop-motion wheel and having a narrower prolongation whereby it rejects a coin of improper size, a stop-perforation I⁹ extending from the groove I⁶ to the slot I⁷, a pin J J' spring-supported in perforation I⁹ with its ends flush with the bottom of the groove and side of the slot and free to move into the slot, a spring-pawl having its end pressed against the bottom of groove I⁶ and adapted to engage perforation I⁹, a ratchet-stop 40 for preventing motion of the drum in a reverse direction and a coin-receiver arranged to receive the coin after it has actuated the stop-wheel.

8. In a prepayment-meter, the combination 45 of the rotatable plug-cock casing F having a stop-motion wheel F³ secured to it, said wheel having symmetrically-disposed slots formed in its rim and concave segmental facets formed between said slots with a drum I 50 adapted to fit in the concave facets of wheel F³ and having a recessed portion adapted to clear said wheel and having a coin-slot arranged to retain a coin of proper size in position to engage and actuate the stop-motion 55 wheel when the drum is rotated and a meter-actuated plug-cock G working in the casing F as described.

WM. E. GIBBS.
